UNITED STATES PATENT OFFICE.

THEODOR KOPF, OF UERDINGEN, GERMANY.

AUTOMATIC DISCHARGING DEVICE.

No. 866,204.

Specification of Letters Patent.

Patented Sept. 17, 1907.

Application filed March 4, 1907. Serial No. 360,612.

To all whom it may concern:

Be it known that I, THEODOR KOPF, a subject of the German Emperor, and a resident of Uerdingen-Rhein, Mörserstrasse 149, Germany, have invented certain new and useful Improvements in Automatic Discharging Devices, of which the following is a specification.

The invention relates to a device for automatically emptying receptacles of all kinds, and should be particularly useful as a discharging or unloading device for wagons.

The invention consists essentially in the formation and arrangement of the usual discharging boards in such a way that on releasing a catch they come into the open position under the pressure of the weight of the load, and after unloading automatically return again into the closed position under the action of the power produced in discharging. For this purpose the discharging boards are so situated that instead of being loosely suspended in the usual way on the walls of the receptacle or wagon box, they can move towards the outside on opening so that after unloading they move back again into the closed position under the influence of their own weight.

In the drawing a form of construction of the invention is shown applied to a railway wagon, the wagon being shown in a vertical section. One of the unloading boards is shown in the closed position, and the other in the open position.

The frame of the wagon box *a* rests in the usual way on the axles *b*. The side walls *c* and *d* of the wagon box are obliquely arranged, and the lower parts are constructed in the form of movable plates *e* and *f*. On the upper end of each of these plates are arranged two or more blocks for the rollers *h*, which run on the rails *i* fastened on the wagon box.

On or near the lower ends of the plates *e* and *f* blocks *k* are fitted for the rollers *l* which run on the rails *m*. *n* and *o* are bolts which stand under the influence of springs *p*; these bolts are connected with the levers *q* and *r*, which are rigidly attached to the shafts *s* and *t*. The shafts *s* and *t* are mounted so that they can be turned by the hand levers *u* and *v*. *w* are guiding plates for the material which is being discharged. *x* designates the center of gravity of the plates *e* and *f*.

The operation of the device is as follows: When one of the bolts *n* and *o* has been drawn back by means of the hand lever *u* or *v* of the shafts *s*, *t* and the levers *q*, *r*, that is one of the plates *e*, *f* unbolted, then the pressure exercised on the plate by the charge causes it to move towards the side, whereby the center of gravity *x* of the plate is at the same time raised. This movement of the plate is limited by means of any suitable arranged stop, so that it does not reach a perfectly vertical position. The material drops down the opening so formed on to the chute plate *w* and holds the plate *e* or *f* in the raised position, from which it

automatically returns to the closed position on account of its own weight. On the return the plate presses back the bolt, which by spring power or a counterpoise has again entered the closed position. When the plate has completely reached its position of rest the bolt by the action of the spring or counterpoise slides forward again and thereby bolts the plate. If the wagon is to be discharged towards both sides, then the bolts must be drawn back by means of the two hand levers, whereupon the above described operation takes place on both sides.

It is obvious that the invention is not limited to the form of construction and the form of application here shown.

The various parts of the device may be modified in form and arrangement, and the device may also be applied to other receptacles without the scope of the invention being exceeded.

What I claim as my invention and desire to secure by Letters Patent is:

1. In a discharging device the combination of movable walls obliquely arranged, means to lead said walls outwards and upwards by pressure of the load, said walls being arranged to return by gravity, means to limit the outward and upward movement before the walls reach the vertical position, inclined plates below said movable walls, means for keeping the walls in the closed position, and means for releasing the keeping mechanism, substantially as and for the purpose set forth.

2. In a discharging device the combination of movable walls obliquely arranged, rollers on the top and near the bottom of said obliquely arranged movable walls, oblique rails on which the upper rollers rest, rails on which the lower rollers rest, means for keeping said walls in the closed position, means to release the keeping mechanism, said walls being adapted to return to the position of rest by gravity, inclined plates below said obliquely arranged movable walls, and means to limit the outward and upward movement of the walls, substantially as and for the purpose set forth.

3. In a discharging device the combination of two oblique walls, opposite one another, movably arranged lower parts of said walls, rollers at the top and near the bottom of said movably arranged walls, rails on which said rollers rest, inclined plates below said movably arranged walls, mechanism for keeping said walls in the closed position, means to release the keeping mechanism and means to limit the outward and upward movement of the walls, substantially as and for the purpose set forth.

4. In a discharging device the combination of two oblique walls opposite one another, movably arranged lower parts of said walls, rollers at the top and near the bottom of said walls, rails on which said rollers rest, inclined plates below said walls, bolts adapted to keep said movably arranged walls in the closed position, springs acting on said bolts, means to withdraw said bolts, and means to limit the outward and upward movement of the walls, substantially as and for the purpose set forth.

5. In a discharging device, the combination of two oblique walls opposite one another, movably arranged lower parts of said walls, rollers at the top and near the bottom of said walls, rails on which said rollers rest, inclined plates below said walls, bolts adapted to keep said walls in the closed position, springs acting on said bolts hor-

zontally situated shafts attached to said bolts, hand levers fixed on said shafts and projections suitably adapted to limit the outward and upward movement of the walls, substantially as and for the purpose set forth.

- 5 6. In a discharging device, the combination of two oblique walls opposite one another, movably arranged lower parts of said walls, rollers at the top and near the bottom of said walls, inclined rails on which the upper rollers move, horizontal rails on which the lower rollers move,
10 inclined plates below said walls, bolts adapted to keep said walls in the closed position springs acting on said bolts,

horizontally arranged shafts rigidly connected to said bolts, hand levers fixed on said shafts and projections adapted to limit the outward and upward movement of the walls, substantially as and for the purpose set forth.

15

In testimony whereof I have hereunto signed my name this 18th day of February 1907, in the presence of two subscribing witnesses.

THEODOR KOPF.
